AUTOMOBILE BODY

Antoine Brueyer, Paris, France, assignor to Societe Anonyme Andre Citroen, Paris, France, a corporation of France

Application March 19, 1956, Serial No. 40,663

Claims priority, application France September 22, 1955

Term of patent 14 years

(Cl. D14—3)

FIG. 1.

Fig. 1 is a side elevational view of an automobile body showing my new design;

Fig. 2 is a rear elevational view;

Fig. 3 is a front perspective view;

Fig. 4 is another front perspective view taken at a different angle from that shown in Fig. 3.

I claim:

The ornamental design for an automobile body, substantially as shown.
